This technical drawing illustrates a complex gear assembly, likely a planetary gear system, with the following numbered components:

- 11: A gear located on the left side of the assembly.
- 12: A gear located on the right side of the assembly.
- 13: A gear located on the left side of the assembly.
- 14: A gear located on the right side of the assembly.
- 15: A gear located on the left side of the assembly.
- 16: A gear located on the right side of the assembly.
- 17: A gear located on the left side of the assembly.
- 18: A gear located on the right side of the assembly.
- 19: A gear located on the left side of the assembly.
- 20: A gear located on the right side of the assembly.
- 21: A gear located on the left side of the assembly.
- 22: A gear located on the right side of the assembly.
- 23: A gear located on the left side of the assembly.
- 24: A gear located on the right side of the assembly.
- 25: A gear located on the left side of the assembly.
- 26: A gear located on the right side of the assembly.
- 27: A gear located on the left side of the assembly.
- 28: A gear located on the right side of the assembly.
- 29: A gear located on the left side of the assembly.
- 30: A gear located on the right side of the assembly.
- 31: A gear located on the left side of the assembly.
- 32: A gear located on the right side of the assembly.
- 33: A gear located on the left side of the assembly.
- 34: A gear located on the right side of the assembly.
- 35: A gear located on the left side of the assembly.
- 36: A gear located on the right side of the assembly.
- 37: A gear located on the left side of the assembly.
- 38: A gear located on the right side of the assembly.
- 39: A gear located on the left side of the assembly.
- 40: A gear located on the right side of the assembly.
- 41: A gear located on the left side of the assembly.
- 42: A gear located on the right side of the assembly.
- 43: A gear located on the left side of the assembly.
- 44: A gear located on the right side of the assembly.
- 45: A gear located on the left side of the assembly.
- 46: A gear located on the right side of the assembly.
- 47: A gear located on the left side of the assembly.
- 48: A gear located on the right side of the assembly.
- 49: A gear located on the left side of the assembly.
- 50: A gear located on the right side of the assembly.

UNITED STATES PATENT OFFICE

PARL O. ECKELS, OF CLEVELAND, OHIO, ASSIGNOR TO THE ECKELS ENGINEERING CORPORATION, OF CLEVELAND, OHIO

SWASH PLATE

Application filed October 1, 1931. Serial No. 566,328.

This invention relates to pumps for pumping or compressing fluids and has special reference to improvements in the type of pump or compressor shown and described in my copending application for patent filed May 31, 1930, and bearing Serial Number 458,577.

More particularly the present invention relates to improvements in the swash plate shown in said prior application.

In the construction as disclosed in said prior application the sleeve carrying the swash plate is held concentrically of the driving shaft by an anti-friction bearing surrounding the shaft within the sleeve. For practical reasons it is necessary to use standard sizes of ball bearings but, if such standard sized bearings are used, it becomes impossible from the standpoint of proper engineering construction to use a driving shaft above a certain maximum diameter. Because of this limitation of the size of the shaft in relation to the sleeve diameter it is necessary, in the former construction, to very considerably enlarge the overall dimensions of the machine for any increase in shaft size made necessary in the construction of machines of larger capacities. For instance, if it is desired to double the capacity of a machine designed for a given capacity the strength of the driving shaft must be substantially doubled with corresponding increase in size. A standard ball bearing of size to fit the larger shaft will be of such external diameter as to require a much larger sleeve than the smaller machine. This again will necessitate larger thrust bearings and other parts so that finally the entire machine has been greatly enlarged.

One important object of the invention is to so improve the swash plate arrangement in devices of this character as to eliminate the use of anti-friction bearings between the shaft and sleeve and thereby permit the use of a shaft of any desired size without making necessary any increase in the overall dimensions of the machine.

In the swash plate arrangement of said prior application the pistons carry balls which rest on the swash plate adjacent its periphery. As the swash plate is oscillated

these bearing balls ride in and out of the swash plate to a certain degree because the balls are held by the pistons to move in a straight line while the swash plate periphery describes an equatorial zone of a sphere. This travel of the balls, even though it is slight in each case, aggregates to an extent producing considerable friction and heat.

A second important object of the invention is to improve the connection between the swash plate and the pistons actuated thereby that all sliding friction will be eliminated and thus there will be substantially no generation of heat at these points.

Devices of this kind are generally made to pump or compress at a certain fixed rate, the cylinders each having a definite capacity for that purpose. In order to provide pumps or compressors of different capacities it has been customary to vary the dimensions throughout. That is, if the areas of the cylinders are to be increased the diameter of the entire machine would be increased as well as the diameter of the drive shaft.

A third important object of the invention is to provide a novel construction of devices of this character wherein, by minor changes in details, the capacity of the machine may be made to suit the use to which it is desired to be put.

In devices of this character, as well as in many other mechanisms in the nature of pumps or engines, it is usually desirable to arrange the parts in as compact a manner as possible. In multicylinder devices it is usual to employ an intake or supply manifold and an outlet or exhaust manifold so that single supply and exhaust pipes may be connected to the several cylinders.

A fourth important object of the invention is to provide a novel manifold arrangement wherein the exhaust and supply manifolds are arranged to form a single unit thus rendering the mechanism compact.

Also to the end of obtaining compactness a fifth important object of the invention is to provide a novel valve arrangement for use in connection with such a manifold whereby a single valve element serves to place the several cylinders successively in commun-

cation with the intake manifold and then with the exhaust manifold.

With the above and other objects in view as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

Figure 1 is a view of the improved device taken longitudinally thereof and partly in section on a plan passing through the longitudinal axis of the device.

Figure 2 is a section on the line 2—2 of Figure 1.

Figure 3 is a vertical section on the axis 20 of a modified form of the invention, the view showing one end only of a pump especially adapted for the pumping of liquids.

Figure 4 is a half end view of this modification.

Figure 5 is a face view of a valve plate used in this modification.

Figure 6 is an edge view, partly in section from the intake side of Figure 5.

Figure 7 is a view similar to Figure 6 from the exhaust side of the plate.

Figure 8 is a detail view showing the manner of seating certain piston rods on the swash plate.

In the present embodiments of the invention there is provided a main or driving shaft 10 driven by any suitable means not deemed necessary here to be shown. Surrounding the central portion of this shaft is a sleeve 11 which is of considerably greater diameter than the shaft here shown so that, if desired, the shaft size may be increased. The sleeve 11 is arranged with its axis at an acute angle to the shaft 10. Fixed on the shaft 10 at each end of the sleeve is a cam 12. Each cam 12 includes a disc portion and the confronting faces of these disc portions are bevelled in planes at right angles to the axis of the sleeve. Each cam 12 has in its bevelled face a recess 13 into which extends a respective end of the sleeve 11. A swash plate 14 is fixed firmly on the center of the sleeve 11 and a ball race 15 is forced on the sleeve on each side of the swash plate. Coacting ball races 16 surround the sleeve adjacent its ends and rest on the bevelled surfaces of the cams 12. These races 16 are, as is usual, slightly larger than the sleeve so that the races 16 may revolve freely on the sleeve without friction thereagainst. The usual balls 17 are provided between the races 15 and 16. It is to be noted that the balls and races tend to hold the sleeve in correct angular relation to the shaft at all times and the recesses 13 are sufficiently large that a slight clearance exists between the sleeve 11 and the walls of said recesses under normal

conditions. However, wear or failure of the ball bearings will not injuriously affect the mechanism since the engagement of the sleeve ends in the recesses will prevent any injurious displacement of the sleeve.

By means of the mechanism just described rotation of the shaft will set up a gyratory motion in the swash plate while yet permitting the swash plate to perform such gyratory movement without rotation on its axis.

Spaced from the respective cams 12 are body ends or heads 18 each having a central hollow cylindrical bearing boss 19 wherein is mounted a ball bearing 20 supporting the shaft 10. Each of these bearing bosses has 80 its outer end closed by a cap plate 21.

A series of hollow cylinder bosses 22 are spaced around the periphery of each end 18, these bosses extending from the respective ends toward each other and the bosses on one end being axially aligned with respect to the bosses on the other end so that they form pairs with the bosses of each pair on opposite sides of the swash plate 14. Each of these bosses is made of sufficient diameter to suit the largest machine within desired limits and in the proximal ends of the bosses are liners 23 which form the cylinders proper. These liners are preferably press fitted into the bosses and the internal diameters of the 95 liners are made to suit the capacity for which the particular machine is designed. Thus by simple variation in the internal liner diameter the capacity of the machine may be varied correspondingly. Slidably mounted in each liner is a hollow piston 24, the open ends of these pistons facing the swash plate. In the open end of each piston is screwed a plug 25 having a socket or recess 26 for the reception of a pin or piston rod 27. This pin or rod has each end rounded and one of the rounded ends is seated against the inner end of the socket while the other end projects from the socket and engages the swash plate, the latter being provided with a shallow seat or 110 depression 28 to receive such end as best shown in Figure 8. The sockets 26 are of slightly greater diameter than the diameter of the pins or rods 27 so that the latter may oscillate to a sufficient extent to maintain the 115 swash plate ends of the pins in their seats. By this means no lineal movement of the pins on the swash plate with the accompanying friction can take place. Moreover, it was observed in machines constructed in accordance 120 with the aforesaid prior patent that the swash plate oscillated about its axis over a considerable arc during the running of the machine but it was also found that this oscillatory motion required but little force for its 125 prevention, the mere grasping of the edge of the plate between the thumb and forefinger being sufficient to arrest all motion of this character. Consequently, the seating of the pins or rods 27 in shallow seats in the swash 130

plate as herein disclosed is sufficient to prevent such oscillation and the attendant frictional wear and heating. In order to maintain the pins or rods in proper engagement with the swash plate each plug 25 is provided at its projecting end with an annular groove and in these grooves are seated the ends of spring clips 30 which are centrally bowed inwardly both to provide means for holding the clips from moving from proper positions by engagement with the edge of the swash plate and to improve the resilient action of the clips. Each of these clips holds the ends of an alined pair of the pistons in proper spaced relation so that as one piston moves into its cylinder the other moves out.

The two heads or ends are connected by tie bolts 31 and are surrounded by a casing 32 which has a sump or oil reservoir portion 33. An oil pump is provided at 34 of the usual cylinder and plunger type, the plunger projecting from the cylinder to rest against the swash plate and be there held by a spring 35. This pump receives oil through a pipe 36 leading from the sump 33 and delivers oil through a pipe 37 to the upper part of the machine, the oil dripping from the pipe 37 onto the operating parts in the middle of the machine.

The form of the invention shown in Figures 1 and 2 is especially adapted for use as a compressor of gaseous fluids such as air. In this form there is fitted into the outer end of each cylinder boss a valve cage or plug 36. An intake passage or port 37' extends through this cage and is provided at its inner end with a seat for the reception of an inwardly opening spring pressed check or inlet valve 38. Also the cage is provided with a second passage 39 therethrough having an outwardly facing valve seat at its inner end and provided with a branch passage 40 leading to a channel 41 extending circumferentially around the cage. A ball valve 42 is spring pressed against the last named seat and thus forms an outwardly opening valve. Each head has a wall 43 connecting the bosses 19 together and to the boss 22 parallel to the end 18 and the bosses 19 are connected to each other by short walls 44 one of which is tapped as at 45 for connection of a delivery pipe. This wall arrangement forms a receiving chamber 46 communicating with the channels 41 by ports 47.

Surrounding each group or set of cylinder bosses is a rib 48 and radiating fins 49 extending longitudinally of the outer half of each cylinder from the outer or valve end thereof to said rib. A cylindrical hood or housing 50 is fitted over these ribs being seated on bosses 51. The edge of this hood is spaced from the rib 48. The hood 50 is provided with ports 52 in its end and dust filters 53 are arranged to cover the ports 52.

A fan 54 is fixed on the shaft within each hood.

In this form of the invention as the shaft rotates the fans draw air through the filters into the supply chambers producing a slight pressure in these chambers. As the swash plate gyrates each piston 24 is reciprocated and in its movement of protraction from its cylinder draws air into the cylinder through the passage 37. As the piston is pushed back into its cylinder the air in the cylinder is compressed and driven out through the passage 39, branch 40, groove 41 and port 47 into the receiving chamber 46. Any excess air from the supply chambers flows down along the ribs 49 and thus carries off the heat and keeps the cylinders cool.

In the form of the invention shown in Figures 3 to 7 inclusive, the arrangement is particularly adapted for pumping liquids. In this arrangement the valve cages are omitted and the outer or head ends of the cylinders are left open being covered by an annular rim 55 forming part of a rotary valve having its hub 56 fixed on the shaft 10 so that the valve revolves as the shaft is rotated. One semi-circular segment of the rim 55 constitutes the inlet side while the other semi-circular segment constitutes the outlet side. In the outer face of the inlet side there is provided an annular channel 57 and extending from this channel is a series of inlet ports 58 adapted to successively register with the open ends of the cylinders and opening through the inner face of the rim. The outlet side of the rim is provided on its inner face with an arcuate channel 59 from whence ports 60 open out through the peripheral edge of the rim. An annular member 61 is rabbed at 62 to receive the rim 55, the member 61 covering the outer face and peripheral edge of the rim. The member 61 is thus provided with a plane inner face confronting the outer face of the rim and with a cylindrical face confronting the peripheral edge of the rim. In the plane inner face is provided an inlet channel 63 extending entirely around the member 61 and is tapped as at 64 to provide means whereby a supply or suction pipe may be connected to the member 61 to communicate with the channel 63. An annular outlet channel 65 is formed in the cylindrical face of the member 61 and the member is tapped as at 66 to provide means for connection of an outlet pipe communicating with the channel 65. Packing 67 is provided where needed. The channel 63 and channel 57 are constantly in registry and the ports 60 open constantly into the channel 65.

In this form the parts are so arranged that during the retraction of any piston the ports 58 are successively brought into registry with the cylinder end so that fluid flows into the cylinder. As the piston reaches the end of its stroke the last of the ports 58 move out

of registry and immediately thereafter the channel 59 moves into registry with the cylinder end so that the retractive movement of the piston forces the fluid out of the cylinder and through the ports 60 into the channel 65 5 from whence it flows out through the delivery pipe. The member 61 thus constitutes a combined intake and exhaust manifold.

It is to be observed that not only may the cylinder capacities be varied at will by the 10 employment of proper liners but the capacity of these cylinders may also be varied by changing the stroke of the pistons. This is readily done by changing the cam members 12, members with greater throw or angularity 15 of face being provided to increase the stroke and with less throw or angularity to provide shorter stroke.

It is also to be noted that while the present device has been shown as a pump yet the 20 action will be reversed if fluid is supplied to the cylinders under pressure and the exhaust side of the mechanism opened for free exhaust so that the mechanism may be used as an engine. In other words, by means of this 25 mechanism rotary motion may be changed to reciprocating motion or reciprocating motion may be changed to rotary motion. It is therefore to be understood that wherever cylinders 30 are mentioned in the claims appended hereto these cylinders are to be understood as either pump or engine cylinders according to the use to which the device is put. Also, it is to be understood that, when used as an engine 35 the device will be connected to a suitable source of supply of fluid under pressure such as a steam boiler, so that the pistons will be caused to reciprocate by the action of this fluid under pressure and thereby reciprocity movement will be converted into rotary 40 movement.

There has thus been provided a simple and efficient device of the kind described and for the purpose specified.

It is obvious that minor changes may be 45 made in the form and construction of the invention without departing from the material spirit thereof. It is not, therefore, desired to confine the invention to the exact 50 form herein shown and described, but it is desired to include all such as properly come within the scope claimed.

Having thus described the invention, what is claimed as new, is:

1. In a swash plate apparatus, a shaft, a 55 swash plate having a central opening through which said shaft passes, said opening being of greater diameter than the shaft to permit rotation of the shaft independently of the swash plate, an operative mechanism connecting the shaft and swash plate and arranged to effect gyratory movement of the swash plate without rotating the plate, cylinders 60 arranged in series on a circle concentric with the shaft, pistons in said cylinders,

and piston rods each engaged at one end with a piston for free oscillatory movement with respect to the piston and having its other end engaging the swash plate, the last mentioned end of the piston being rounded and the swash plate having a shallow recess in which said rounded end is received. 70

2. In a swash plate apparatus, a shaft, a swash plate having a central opening through which said shaft passes, said opening being of greater diameter than the shaft to permit rotation of the shaft independently of the 75 swash plate, an operative mechanism connecting the shaft and swash plate and arranged to effect gyratory movement of the swash plate without rotating the plate, cylinders arranged in series on a circle concentric with the shaft, pistons in said cylinders, rod sockets mounted in the ends of the pistons adjacent the swash plate, each of said sockets having a rod seat confronting the swash plate and the swash plate having shallow depression confronting the pistons and forming other rod seats, and rods having rounded 80 ends and each having one end seated in a respective first mentioned rod seat and its other end seating in the corresponding shallow depression. 85

3. In a swash plate apparatus, a shaft, a swash plate having a central opening through which shaft passes, said opening being of greater diameter than the shaft to permit rotation of the shaft independently of the 90 swash plate, an operative mechanism connecting the shaft and swash plate and arranged to effect gyratory movement of the swash plate without rotating the plate, cylinders arranged in series on a circle concentric with the shaft, pistons in said cylinders, means connecting each piston with a 95 respective point on the swash plate and maintaining contact with the plate at the same point throughout the gyratory movement of the plate, end members wherein said shaft is journaled, hollow cylinder bosses carried 100 by said end members and having the cylinders fitted in the ends against the swash plate, and valve cages provided with inlet and outlet valves mounted in said bosses at the ends remote from the swash plate. 110

4. In a swash plate apparatus, a shaft, a swash plate having a central opening through which said shaft passes, said opening being of greater diameter than the shaft to permit rotation of the shaft independently of the 115 swash plate, an operative mechanism connecting the shaft and swash plate and arranged to effect gyratory movement of the swash plate without rotating the plate, cylinders arranged in series on a circle concentric with the shaft, pistons in said cylinders, means connecting each piston with a respective point on the swash plate and maintaining contact with the plate at the same point throughout the gyratory movement of the plate, end 120

- members wherein said shaft is journalled, hollow cylinder bosses carried by said end members and having the cylinders fitted in the ends against the swash plate, valve cages 5 provided with inlet and outlet valves mounted in said bosses at the ends remote from the swash plate, hoods each mounted on a respective end member and having a ported end closure spaced from the end member, 10 air filtering means covering the ports in the end closure, fans each mounted on said shaft in a respective hood and arranged to draw air through said filtering means, and heat radiating fins carried by said cylinder bosses and arranged in the path of air from the fan. 15
5. In a swash plate apparatus, a shaft, a swash plate having a central opening through which said shaft passes, said opening being of greater diameter than the shaft to permit 20 rotation of the shaft independently of the swash plate, an operative mechanism connecting the shaft and swash plate and arranged to effect gyratory movement of the swash plate without rotating the plate, cylinders 25 arranged in series on a circle concentric with the shaft, pistons in said cylinders, means connecting each piston with a respective point on the swash plate and maintaining contact with the plate at the same point throughout 30 the gyratory movement of the plate, hollow end members forming air receiving chambers and each having a central bearing wherein said shaft is journalled, hollow cylinder bosses carried by said end members and each having 35 a lateral port communicating with a respective chamber, said cylinders being fitted into the ends of the bosses adjacent the swash plate, and valve cages each fitted in the remaining end of a cylinder boss and 40 having a peripheral groove wherewith the port of the boss registers, said cage being provided with valved inlet and outlet passages, each outlet passage opening into the groove of the respective cage. 45
6. In a swash plate apparatus, a shaft, a swash plate having a central opening through which said shaft passes, said opening being of greater diameter than the shaft to permit rotation of the shaft independently of the 50 swash plate, an operative mechanism connecting the shaft and swash plate and arranged to effect gyratory movement of the swash plate without rotating the plate, cylinders 55 arranged in series on a circle concentric with the shaft, pistons in said cylinders, means connecting each piston with a respective point on the swash plate and maintaining contact with the plate at the same point throughout the gyratory movement of the 60 plate, hollow end members forming air receiving chambers and each having a central bearing wherein said shaft is journalled, hollow cylinder bosses carried by said end members and each having a lateral port communicating with a respective chamber, said 65
- cylinders being fitted into the ends of the bosses adjacent the swash plate, valve cages each fitted in the remaining end of a cylinder boss and having a peripheral groove wherewith the port of the boss registers, said cage being provided with valved inlet and outlet passages, each outlet passage opening into the groove of the respective cage, hoods each mounted on a respective end member and having a ported end closure spaced from the end member, air filtering means covering the ports in the end closure, fans each mounted on said shaft in a respective hood and arranged to draw air through said filtering means, and heat radiating fins carried by 70 said cylinder bosses and arranged in the path of air from the fan. 75
7. In a swash plate apparatus, a circular series of cylinders, a hollow end member forming an air receiving chamber and supporting said cylinders, each of said cylinders having port communication with said chamber, and a valve cage for each cylinder fitted in the cylinder and having a peripheral groove registering with the port of the respective cylinder, said cage being provided with a valved inlet passage extending therethrough and with a valved outlet passage communicating with the groove. 80
8. In a swash plate apparatus, a circular series of cylinders, a hollow end member forming an air receiving chamber and supporting said cylinders, each of said cylinders having port communication with said chamber, a valve cage for each cylinder fitted in the cylinder and having a peripheral groove registering with the port of the respective cylinder, said cage being provided with a valved inlet passage extending therethrough and with a valved outlet passage communicating with the groove, a hood mounted on said end member and covering the valved ends of said cylinders, said hood having an end spaced from the end member and provided with air inlet means arranged to filter the admitted air, a fan revolvably mounted in said hood to draw air into the hood through said inlet means, and cooling fins for said cylinders arranged in the path of air from the fan. 90
9. In testimony whereof I affix my signature. 95
